APPLIQUÉ TYPE DOOR PANEL OR SIMILAR ARTICLE

James E. Thompson, Torrance, Calif., assignor to Palazzo
Panels, a corporation of California

Filed Aug. 5, 1965, Ser. No. 86,470

Term of patent 14 years

(Cl. D13—1)

I claim:
The ornamental design for an appliquéd type door panel or similar article, substantially as shown and described.
